UNITED STATES PATENT OFFICE

OSCAR S. HUBBARD, OF FARMLAND, INDIANA

WRECKING-TRUCK

Application filed June 28, 1930. Serial No. 464,499.

This invention relates to improvements in wrecking-trucks of the type in which a hoist device is embodied, said device comprising a sheave over which a tackle is operated, either manually or by mechanical power, for the recovering of disabled automobiles.

In many instances in which the pull exerted through the tackle is in a direction other than vertical, the truck, (although it may be of relatively large size, and even though wheels may be blocked), will yield its position; the hoist device thereby being rendered ineffective.

I am aware that inventions have heretofore been patented, having for their purpose the propping of the hoist device, or the staying of the wheels of the truck. Such devices however, are ineffective in so far as facilitating the pull of the load from its dead position is concerned, unless the truck can be anchored to some immovable object such as a tree or a building structure.

To provide means whereby the above named disadvantages may be overcome, is the general object of my invention. The said general purpose, as well as other and more specific aims of my invention are accomplished by the new construction, combination and arrangement of parts described in the following specification, and illustrated in the accompanying drawings. The invention is defined in the claims.

The several parts of the invention are identified by suitable characters of reference applied to them in the different views in the drawing, in which—

Figure 1 is a side view of my improved wrecking-truck.

Figure 2 is a rear view of Figure 1.

Figure 3 is a top plan view of the rear portion of Figure 1.

Figure 4 is an enlarged detail view of the upper portion of the strut, and of its connections with the mast.

Figure 5 is an end view taken in the direction of arrow 5 in Figure 4.

Figure 6 is an enlarged detail view of the lower portion of the strut, and of one of the stay bars, and its connection with the truck rear axle housing.

Figure 7 is an enlarged view showing the changed positions of the side member of the strut, and of the handle levers when the strut will have been lowered to the dotted line position indicated in Figure 1.

Figure 8 is a detail view showing a form of toe block application to the foot bar.

The embodiment of my invention as same is described and illustrated herein is of the form preferred in general, and in detail, for a truck of common construction. In such a truck the hoist device and tackle equipment comprises a usual rearwardly slanted mast structure, a sheave pulley, cable and winch.

My invention provides a compression member, or strut, carried in a suspended position by the frame portion of the hoist device, means whereby the said strut may be lowered to a plane substantially coincident with the plane of the road surface, and a stay element between a part of the frame of the truck and the lower portion of the said strut.

In practicing the invention the strut is disposed in the lowered position. The several parts as above described function in such manner, that immediately upon the establishment of a tension in the cable, (such tension being incident to a pull on the load), the strut is pressed firmly against the road surface or ground, and is there held immovable. The truck being connected to the strut by the stay member, it is held securely against movement.

The mast structure which is secured to the floor A of the truck frame, comprises the usual complementary opposed metal bars B and B, the uprights C and D, and the braces E and F. Carried by a block G, at the head of the mast, is a sheave pulley H. From a winch J a usual cable K is operated over the said pulley.

The strut or stiff leg structure comprises opposed complementary slanted sides, consisting of angle bars 1 and 1, three inches by two inches in cross section, retained at spaced distance apart by a foot bar 2 which consists of a three by four inch T bar. Joined by a hinge pin 3 to the upper end of each of the side bars 1, is a hand lever 4. Spaced from the center of said hinge pin 3 is a latch pin hole 5. In each of said hand levers 100

4, at a given distance from the pivot pin 3, is a bore which is journaled on a bearing pin 6. This bearing pin 6 has a head 6a and journal 6b and it is drawn to and secured rigidly in engagement with the liner blocks 7 by a nut 8. In each of the said lever bars, at points equidistant from the pivot pin 3, are pin holes 9 and 10. The distance between the center of pivot pin 3 and the center of pin hole 9, and the distance between the center of pivot pin 3 and the center of pin hole 10, is identical with the distance between the center of pin 3 and the pin hole 5. In folded status the hand levers 4 and sides 1 and 15 of the strut appear as shown in Figure 1, the strut being at the raised position. A latch pin 12 (which may be suspended from one of the parts by a small chain 12a inserted in the pin hole 5 of the strut bar 1 and the pin hole 9 of the hand lever), latches the parts in the position shown, the leg 4a of the hand lever staying the parts. Extending from the foot bar 2, and to which said bar they are connected by bolts 14 are stay bars 15 and 15. 20 At the free end of each of these stay bars is a head piece 16, which is provided with a stirrup 17. By the said stirrups, which are retained by the nuts 18, the stay bars are held in engagement with the rear axle housing L 25 of the truck.

My invention, in readiness for use, appears as shown in Figure 1, the strut being retained at the elevated position. The parts are so proportioned and they are arranged in such relation that the foot bar 2 occupies position immediately against the rear edge of the foot board A' of the truck. Thus, the parts are sufficiently elevated for road clearance, and they do not interfere with free access to the floor of the truck. To practice the invention the truck will have been placed in position desired for commencing the work of lifting and perhaps the budging or the shifting of the dead load (usually a disabled automobile). The latch pins 12 are then removed. By swinging the hand levers 4 on the bearing pins 6 to the reverse position indicated by the dotted lines in Figure 1 and in the view shown in Figure 7, the strut will have become lowered to the dotted line position as shown in Figure 1. The latch pins 12 are then inserted in the pin holes 5 of the side bar 1 and in the pin hole 10 of the hand lever. Thus the parts are latched in the position shown in Figure 7, the leg 4b of the hand lever staying the parts.

For a truck which is intended for the work required usually by garages and service stations, the throw of the hand levers is of length to lower the strut to a plane substantially coincident with the plane of the road surface. It will be understood that in instances where the truck is of necessity located on grounds that do not afford a footing for the strut, suitable footing of timber or

other material may be provided. A foot bar of structure suitable for slippery or ice covered surface is shown in Figure 8, spaced metal toe blocks 20 being used. The strut having been poised as described, the winch is 70 operated.

Immediately upon the establishment of a tension of the cable, the downward urge of the mast B causes a similar urge of the strut. Thus the strut is pressed and with its foot bar it is maintained immovable. The truck being connected by its rear axle structure, and the stay bars 15, to the said strut, the said truck in turn is automatically held against movement. By reason of the stability thus afforded for the mast, the work of lifting and moving and preparing for the towing in of the disabled automobile is materially facilitated. Moreover, it renders possible the performance of materially heavier duty, by wrecking trucks of relatively light weight. After the dead load will have been lifted and preparations will have been completed for towing, the strut is then returned to its normal or raised position as 90 shown in Figure 1, the hand levers being held in place by the latch pins 12, in the manner as hereinbefore described.

My invention is available as a part of wrecking truck equipment as it leaves the 95 manufactory, or it may be supplied as an attachment suitable for wrecking trucks already in service. It will be understood that in embodying the invention in trucks wherein the hoist devices may be of the crane or derrick type, and of different capacities and styles, the structure and details of the invention may be modified within the scope of the invention as defined by the appended claims 100 without departure from the invention.

What I claim as my invention is—

1. In a wrecking-truck having a hoisting device, a hand lever fulcrumed on a fixed part of said hoisting device, a footed strut having its upper portion pivotally connected to said hand lever whereby when the hand lever is swung on its fulcrum the strut may be raised or lowered, and a stay member retained between the lower portion of the strut and the frame of the truck.

2. In a wrecking-truck having a hoisting device, hand levers fulcrumed on opposite sides of the frame of said hoisting device, a footed A-shaped strut having its opposed upper portions pivotally connected to said hand levers, whereby when the hand levers are swung on their fulcrums, the strut may be raised or lowered, and a stay member loosely connected between the lower portions of the sides of said strut and the frame of the truck.

3. In a wrecking-truck having a hoisting device, the mast of which extends rearwardly, hand levers fulcrumed on the sides of the mast, a footed strut having the upper ends 130

of its side members pivotally connected with the said hand levers, and spaced oppositely disposed stay members retained between the lower portion of the strut, and the rear axle 5 casing of the truck.

4. In a wrecking-truck having a hoisting device comprising a slanted mast structure, hand levers fulcrumed on opposite sides of the mast structure at a location near the end 10 thereof, a footed strut having opposed sides the base portion of which said strut is adapted to become seated on the ground, and the upper ends of its sides being pivotally connected to the said hand levers, whereby when 15 the hand levers are swung on their fulcrums, the strut may be raised or lowered, latching means to hold the hand levers and the strut in united relation when in the raised or in the lowered position, and stay devices between 20 the lower portion of the strut and the rear axle casing of the truck.

5. In a wrecking-truck having a hoisting device, a footed strut, hand levers fulcrumed on the hoist device frame, and having connection with the upper ends of the footed strut whereby the strut may be moved to and from, and may be maintained in raised or lowered positions, and a stay member between the 25 strut and the frame of the truck.

30 6. In a wrecking truck having a derrick thereon, a footed strut, a stay member retained between the lower portion of the strut and the frame of the truck, and a movable connecting member between the said derrick 35 and the upper portion of the strut, the said connecting member being fulcrumed on the derrick and being operable to move the said strut to and from, and to retain same in, raised or lowered position.

40 7. In a wrecking truck having a derrick thereon, a footed strut having opposed slanted sides and being provided with a base portion adapted to be seated on the ground, stay members retained between the ends of 45 the base portion of said strut and the rear axle casing of the truck, and movable connecting members between the sides of the said derrick and the upper portion of the sides of said strut, said connecting members being 50 fulcrumed on the sides of the derrick and being operable to move the said strut to and from, and to retain same in, raised or lowered position.

55 8. In a wrecking truck having a hoisting device comprising a slanted mast structure, hand levers fulcrumed on opposite sides of the mast structure, the weight arm of each of said hand levers being provided with spaced holes and having a transverse flange, 60 a footed strut having opposed sides, the base portion of which said strut is adapted to become seated on the ground, and the upper ends of its sides being pivotally connected to the weight arms of said levers at points in 65 the latter between said holes therein, and

there being a hole in each of the sides of the footed strut to register with a hole in the said hand levers when the latter are at raised or lowered position and the flanges thereof are in alignment with the sides of the said footed strut, latch pins carried by said footed strut adapted to be inserted through the holes in the sides of the footed strut and through the holes in said hand-levers, and stay members between the lower portion of the strut, 70 and the frame of the truck. 75
